UNITED STATES PATENT OFFICE

2,310,739

FUEL SUPPLY AND CARBURETING SYSTEM
FOR INTERNAL COMBUSTION ENGINESJoseph C. Lang, Pittsburgh, Pa., assignor to
Boji Corporation, Pittsburgh, Pa., a corpora-
tion of Delaware

Application June 27, 1940, Serial No. 342,742

6 Claims. (Cl. 261—21)

This invention relates to the fuel supply and carbureting system of an internal combustion engine and is particularly designed for use in a carbureting system wherein fuel is supplied to a wick device from which it is evaporated by the stream of combustion air passing to the engine, the air thereafter being carbureted in a conventional carburetor. The present application is a continuation in part of my copending application Serial No. 285,298, filed July 19, 1939, now issued as United States Patent No. 2,262,013, granted November 11, 1941.

In a copending application of Emery E. Phillips, Serial No. 211,090, filed May 31, 1938, there is disclosed a charge-forming device for internal combustion engines comprising an auxiliary carbureting unit in advance of the main carbureting unit, the auxiliary carbureting unit being provided with a curtain of absorbent material through which the air flows in passing to the main carburetor. This curtain of absorbent material is supplied with fuel so that the air in passing through the curtain, vaporizes some of the fuel before it flows to the main carburetor. In my said application Serial No. 285,298 of which the present application is a continuation in part, I have claimed an improvement in the auxiliary carbureting device per se. In the auxiliary carbureting device disclosed and claimed in my said application Serial No. 285,298, the absorbent material is wrapped about and carried by looped pipe which is perforated, the arrangement being such that fuel may be continuously supplied to one end of the looped pipe and continuously discharged from the other, some of the fuel in flowing through the pipe escaping through the openings in it onto the wick. I have discovered that by connecting the looped pipe, such as that used in the vaporizer of my said application, around the fuel pump of an internal combustion engine and a conventional carburetor into a branch pipe leading from the circuit in which the loop is included, it is not only possible to supply both the booster and the carburetor with fuel from the pump at the same time, but that the system eliminates certain difficulties inherent in fuel supply systems using a pump. The present invention especially eliminates the formation of what is known as a "vapor lock" in the fuel system.

My invention may be readily understood by reference to the accompanying drawing which illustrates certain preferred embodiments there-
of and in which

5 Fig. 1 of the drawing discloses more or less schematically an internal combustion engine with its carburetor and fuel pump and fuel supply tank and the auxiliary carbureting device, the latter being shown in a somewhat dia-
grammatic fashion with the fluid coil in perspec-
tive and other parts in section, the same being
on the air intake of the conventional carburetor;
and

10 Fig. 2 is a fragmentary showing of a modi-
fication.

Referring to the drawing, A designates an in-
ternal combustion engine having a downdraft
15 carburetor B which delivers the carbureted
charge of fuel and air to the engine through a
manifold C, this arrangement being a conven-
tional arrangement now commonly used on mo-
tor cars. The carburetor B is supplied with an
upwardly extending air duct D. At the top of
20 this air duct is mounted the auxiliary carburet-
ing device or auxiliary carbureting device desig-
nated generally as E.

The unit E comprises a bottom pan 2 prefer-
ably formed of sheet metal having an annular
25 trough-like portion 3 therein. The pan 2 is
provided with a centrally positioned cone por-
tion 4 terminating in a cylindrical flange 5, the
flange 5 being for attaching the device to the
air duct D at the top of the carburetor. With-
30 in the cone 4 there is illustrated a spider 6 which
supports a central pin or bolt 7 that extends
upwardly through the top of the device as shown.
Around the rim of the bottom pan 2 is an an-
nular flange 2a.

35 Setting on the bottom pan 2 and fitted within
the flange 2a is a cylindrical shell 8 having
a number of windows or openings 9 formed
therein, this series of windows extending en-
tirely around the device and providing a large
40 total of open area through which air can flow
to the interior of the shell. Fitted over the top
of the shell 8 is a cover member 10 having a
flange 10a that fits about the top of the shell
and having a shoulder portion 10b against which
45 the top of the cylindrical shell abuts. It is pro-
vided with an upwardly offset portion 11 and a
flat top 12. The bolt 7 passes through the top
12, and a wing nut 13 threaded onto this bolt
serves to tightly hold the bottom pan, the shell
50 8, and the cover member 10 in assembled rela-
tion. The structure may be readily dis-assem-
bled upon removal of the wing nut 13.

Within the cylindrical shell or enclosure 8 is
an air filter comprising concentric outer and
55 inner cylindrical screens 14 and 15 with a mass

of loose filtering material 16 therebetween. This material is preferably copper scouring wool, but may be any other suitable non-combustible fibrous or porous filtering mass. The bottom edges of the screens 14 and 15 rest on the bottom pan 2 outside the trough 3, and the shoulder 10b on the cover 10 engages the top edges of these screens. In this way the air filtering structure is maintained in position inside the cylindrical shell 8 and the pan and cover of course prevent the filtering material 16 from becoming displaced.

Spaced inwardly from the outer air filter is a second air filter and back-fire shield or screen comprising outer and inner spaced wire screens 17 and 18 between which is a mass of copper wool or other fire-resistant fibrous material, preferably metallic, 19. This inner air filter and back-fire screen is supported at its bottom on the bottom pan 2 on the portion thereof inside the trough 3 and outside the conical portion 4. The top of this inner filter and back-fire screen abuts against the top 12 of the cover member 10, and the screen is tightly confined against endwise movement between these two members. While the offset portion 11 prevents the inner screen from shifting radially and maintains its concentric with the outer air filter, it is important that the bottom of this back-fire screen be in tight contact with the pan 2 and that the top of this inner air filter or fire screen be tight against the lining on the top portion 12 of the cover 10 so that in the case of a back-fire in the carburetor sending a flame up through the down-draft duct into the space inside the inner air filter, this flame cannot communicate or pass through any space either below or above the inner air filter or back-fire screen, and as an additional guard against this, the top 12 of the cover 10 is preferably provided with an asbestos cover 20 on the inner surface thereof. The asbestos covering 20 not only is an added guard against back-firing around the top of the inner air filter member, but has a dampening effect on sounds so as to make the structure operate more silently than where such material is not provided.

In the space between the inner and outer filter units is the vaporizing unit designated generally as 21. In its preferred form it comprises an upper coil of pipe or tubing 23 and a lower coil of pipe or tubing 24. These two coils are preferably formed from a single length of tubing. The pipe is coiled to form an upper loop or convolution. It is then bent downwardly at 25 and then bent around to form a lower loop 24. One end of the coil 26 is turned vertically downwardly and the other end 27 is also bent vertically downwardly. The two downwardly extending legs of the coils unit pass through the trough and pan 3 and the joint is soldered where these terminals of the coil pass through the pan. The coil is provided with numerous small holes at intervals therealong. Wrapped tightly about the coils 23 and 24 is a layer of fabric or wick-forming material as best shown in Figure 4. The fabric is formed of capillary fibres forming a continuous wick about the two coils, glass wool preferably being used. Extending vertically between the two coils are vertical wick elements 29. The elements 29 are preferably formed by wrapping a continuous strand of corded wick material, preferably of glass wool, around one coil and then around the other in the manner shown in my patent above referred to to provide

more or less regularly spaced strands. This is accomplished, for example, by wrapping the wick material once around the lower pipe and then extending it upwardly and wrapping it once around the upper pipe and thence back to the lower pipe, etc., this forming two series of vertically extending strands 29, one series being spaced inwardly from the other and one series being staggered with respect to the other. By 10 forming the coils 23 and 24 in such manner that they tend to spring apart to a slight extent, this resilience may be relied upon to keep the strands 29 taut.

In operation, liquid fuel is forced into the 15 terminal 26 and flows first through the upper convolution of pipe and then through the lower one and discharges through the terminal 27. Some of the liquid escapes through the perforations along the length of the tubing, wetting the 20 fabric layer 28. This in turn wets the capillary strands 29 causing the wicks to be kept continuously wet with fuel.

The flow of air induced by the operation of the 25 engine is drawn through the windows 9 through the outer filter where the air is broken up into very fine streams. The air then flows around and between the wicks or strands 29 and then flows through the inner filter and back-fire screen to the interior chamber of the device from 30 whence it is drawn down into the carburetor.

In order to maintain the circulation of liquid 35 fuel through the coils as long as the engine is running, the coils are connected directly into the fuel pump system for the engine. The fuel supply line to the engine is designated 30, and 31 is the usual fuel pump. These pumps have a diaphragm which operates continuously when the engine is running. As ordinarily used, there is a flow of liquid, however, only when the carburetor float valve opens to permit the flow of fuel 40 into the carburetor bowl, the pressure developed by the pump being of a very small order.

There is a pipe 32 leading from the pump to the carburetor float chamber. According to the 45 present invention a coupling 33 is placed in the line 32 from which leads a branch pipe 34 that connects through a union at 35 to the coil terminal 26. The other coil terminal 27 is provided with a union 36 to which is coupled a pipe 37, this pipe being coupled at its opposite end to a T 38 in the fluid supply line 30 leading to the pump. It will thus be seen that as long as the engine is operating, the pump 31 may continuously circulate fuel through this continuous 50 loop or circulating system.

In some cases, as indicated in Fig. 2, it may be preferable to return the excess fuel directly to the fuel reservoir R rather than to the fuel line. This is advantageous because it permits any air which is entrapped in the fuel passing through the perforated coil to be discharged into the tank from which it can be vented. To this end I have shown a branch pipe 96 leading from the pipe 37 (not shown in Fig. 2) to the fuel reservoir R. In new car construction it may be convenient to have only a line going to the fuel tank, whereas in the equipment of existing cars it may be convenient to have the excess fuel returned directly to the line 30.

While much of the gasoline or fuel being thus circulated will stay in the circulating system, some of it will, of course, be discharged into the wick structure. It may be discharged into the wick structure at a rate greater than the rate at which it is consumed, as it is desirable to

keep the wick structure quite wet. With this form of the invention, when the wicks become saturated, the excess fuel can drip from the wick structure into the annular trough 3 in the bottom pan 2. To exclude foreign particles that may fall down from the wick, a very fine mesh screen 3x is provided over the top of the drip trough 3. Connected to the annular trough 3 through a union 39 is a drain pipe 40 which is looped at 41 to form a trap, the discharge end of the pipe being connected at 42 to the return line 37. Excess liquid supplied to the wick structure may thus be returned to the fuel circulating system, the trap 41 of course forming a seal to prevent the free induction of air into the system.

The arrangement described provides a relatively large area of wick for contact with the incoming air. The air stream is broken up into small currents by the first air filter. Practically all of the air is brought into intimate contact with some portion of the wick surface from which it evaporates fuel. The air, after picking up the fuel vapor, passes through the inner filter and back-fire screen which also diffuses the flow of air in such manner that the air is drawn into the structure substantially uniformly around the entire structure. The arrangement not only provides an efficient preliminary carbureting unit, but is an effective air cleaner as well. After the device has been used for a period of time, the cover can be removed and the two filtering elements can be lifted out and replaced, or washed in gasoline, thus providing a filter which can be kept clean. The continuous fuel circulating system enables the wicks to be kept abundantly wet, but no loss of fuel is occasioned even where an excess of fuel is supplied to the wicks. By providing what may be termed a shunt or looped fuel circulating system around the pump 31 and into which loop the carburetor is connected, the trouble heretofore encountered from vapor locks is eliminated. By providing a large area of wick surface and a large area of openings 9 for the inlet of air, the air does not move at two high a velocity over the wicks at any given point and the device operates to reduce the hissing or wind noise produced by the suction of the engine.

While I have shown means for collecting fuel which drops off the wick and which is not vaporized in the auxiliary carbureting unit and the pipe 40-41 for returning this excess into the fuel circulating system, it is possible by the use of a metering device at the inlet and outlet sides of the unit, and preferably at both points, to very accurately regulate the dampness of the wick and prevent any such excess. For example, by providing a manually adjusting metering valve 37a in the fuel return line 37, it is possible to prevent any liquid from flowing in the line 37 above the pipe T 42, and all of the fuel circulated by the pump and not consumed by the conventional carburetor will be forced out the openings in the coiled pipe 21. In this case the wick will be very wet. By opening the valve 37a to its fullest extent there will be little pressure built up inside the perforated coil and the wick will be relatively dry. Intermediate stages can be determined by a proper setting of the valve 37a. Even more accurate control can be secured if there is another metering device in advance of the perforated coil. In the drawing, I have illustrated for this purpose a thermally responsive valve 86 in the line 34, but any other

metering valve may be used in its place. The metering valve 86 illustrated has a valve stem 88 which is operated by a bi-metallic member 87. By proper regulation of the metering valves 5 at 86 and 37a very close control of the feeding of fuel to the wick can be maintained and the device can be regulated to give the best results for the particular engine and carburetor with which it is used.

10 In the invention as herein described, it is contemplated that during the operation of the engine, whenever the fuel pump is operating, fuel will be continuously forced to a greater or less extent through the coil and from the coil back 15 into the fluid system, being returned either to the reservoir or the intake side of the pump. The pump will, therefore, never be working against a completely closed circuit as it is at the present time where the closing of the float valve 20 in the carburetor completely shuts off the flow of fluid from the pump which, however, continues to operate. This churning of the fuel by the pump, together with the generation of vapors in the pipe leading from the pump to the carburetor 25 when the temperature under the hood is quite high, gives rise to the blocking of the fuel supply to the carburetor known as a "vapor lock." Since some of the fluid is always kept in circulation through the use of the present invention, the 30 formation of a vapor lock is avoided. At the same time the system disclosed herein provide means whereby both the conventional carburetor and the coil of the vaporizer are supplied with fuel as needed from a common fuel pump. 35 The location of a metering device such as the valve 37a at the outlet side of the coil is particularly desirable in that it assures of the coil being kept sufficiently full of fuel to keep the wick 40 wet and prevent air from being drawn into the system, whereas the provision of the metering orifice at the intake side of the coil without a valve in the outlet pipe may allow the pump to 45 create a suction in the coil which will result in excess air being introduced into the line. By having the discharge side of the coil connected directly to the reservoir instead of leading back to the fuel supply side of the pump, vapors and gases in the system are vented through the vent in the fuel tank.

50 While I have shown and described certain preferred embodiments of my invention, it will be understood that this is by way of illustration and that various changes and modifications may be made therein within the scope of the following claims.

55 I claim as my invention:

1. A fuel system for internal combustion engines comprising a carburetor having an inlet for engine combustion air, a contact device communicating with said air inlet, a fuel pump having an intake connection from a source of fuel and delivery means for feeding fuel to said carburetor and said contact device simultaneously, said contact device having a tubular loop with one end connected to said delivery means and its other end leading to a point in said system on the intake side of said pump, said loop having an intermediate perforated portion communicating with said air inlet for delivering fuel for admixture with the engine combustion air ahead of said carburetor, and means associated with said perforated portion to establish intimate contact between said fuel and said combustion air.

2. A fuel system for internal combustion engines comprising a carburetor having an inlet for

engine combustion air, a contact device communicating with said air inlet, a fuel pump having an intake connection from a source of fuel and delivery means for feeding fuel to said carburetor and said contact device simultaneously, said contact device having a tubular loop with one end connected to said delivery means and its other end leading to a point in said system on the intake side of said pump, said loop having an intermediate perforated portion communicating with said air inlet for delivering fuel for admixture with the engine combustion air ahead of said carburetor, means associated with said perforated portion to establish intimate contact between said fuel and said combustion air, and means for returning excess fuel from said contact device to a point in the system on the intake side of said pump.

3. A fuel system for internal combustion engines comprising a carburetor having an inlet for engine combustion air, a contact device communicating with said air inlet, a fuel pump having an intake connection from a source of fuel and delivery means for feeding fuel to said carburetor and said contact device simultaneously, said contact device having a tubular loop with one end connected to said delivery means and its other end leading to a point in said system on the intake side of said pump, said loop having an intermediate perforated portion communicating with said air inlet for delivering fuel for admixture with the engine combustion air ahead of said carburetor, and wick means adjacent to said perforated portion to establish intimate contact between said fuel and said combustion air.

4. A fuel system for internal combustion engines comprising a carburetor having an inlet for engine combustion air, a contact device communicating with said air inlet, a fuel pump having an intake connection from a source of fuel and delivery means for feeding fuel to said carburetor and said contact device simultaneously, said contact device having a tubular loop with one end connected to said delivery means and its other end leading to a point in said system on the intake side of said pump, metering means in said loop

for controlling fuel flow therethrough, said loop having an intermediate perforated portion communicating with said air inlet for delivering fuel for admixture with the engine combustion air ahead of said carburetor, and means associated with said perforated portion to establish intimate contact between said fuel and said combustion air.

5. A fuel system for internal combustion engines comprising a carburetor having an inlet for engine combustion air, a contact device communicating with said air inlet, a fuel pump having an intake connection from a source of fuel and delivery means for feeding fuel to said carburetor and said contact device simultaneously, said contact device having a tubular loop with one end connected to said delivery means and its other end leading to a point in said system on the intake side of said pump, thermally responsive valve means in said loop for controlling fuel flow therethrough, said loop having an intermediate perforated portion communicating with said air inlet for delivering fuel for admixture with the engine combustion air ahead of said carburetor, and means associated with said perforated portion to establish intimate contact between said fuel and said combustion air.

6. A fuel system for internal combustion engines comprising a carburetor having an inlet for engine combustion air, a contact device communicating with said air inlet, a fuel pump having an intake connection from a source of fuel and a branched delivery conduit for feeding fuel to said carburetor and said contact device simultaneously, said contact device having a tubular loop with one end connected to a branch of said conduit and its other end leading to a point in said system on the intake side of said pump, said loop having an intermediate perforated portion communicating with said air inlet for delivering fuel for admixture with the engine combustion air ahead of said carburetor, and means associated with said perforated portion to establish intimate contact between said fuel and said combustion air.

JOSEPH C. LANG.
